UNITED STATES PATENT OFFICE.

ELIE W. LABOMBARDE, OF NASHUA, NEW HAMPSHIRE.

TOP GLUING MECHANISM.

1,271,730.

Specification of Letters Patent.

Patented July 9, 1918.

Application filed December 22, 1916. Serial No. 136,517.

To all whom it may concern:

Be it known that I, ELIE W. LABOMBARDE, of Nashua, in the county of Hillsborough and State of New Hampshire, have invented certain new and useful Improvements in Top Gluing Mechanism, of which the following is a specification.

This invention relates to the mechanism employed for applying an adhesive, which will be hereinafter referred to as "glue," for the sake of brevity, to paper blanks prior to the latter being folded to form envelops, boxes, etc.

Usually, in box folding or envelop making machines, the blanks, prior to their being folded, are passed over a wheel which carries glue on its periphery. Sometimes it is preferable to have the blanks passing under, instead of over, the glue wheel. A difficulty which has to be overcome when the blanks are passed under the glue wheel is to prevent the escape of glue from the source of supply, or the excessive use of glue. A further difficulty arises when glue dries on the wheel during stoppage of the machine.

The object of my invention is to provide an improved and simple mechanism for applying a stripe of glue to blanks passing along in contact with the under portion of the periphery of a glue wheel, without liability of there being any excess of glue, or waste of glue, during the operation of the machine to which my approved gluing mechanism is applied.

A further object is to provide a device or mechanism of this character which can be easily manipulated to absolutely prevent the escape of any glue when the machine is idle.

A further object is to provide an improved glue wheel mechanism in which the wheel will remain moist when the machine is stopped.

With these and other objects in view, my invention consists in the construction and combination of parts substantially as hereinafter described and claimed.

Of the accompanying drawings:

Figure 1 is a side elevation of a top gluing device or mechanism embodying my improvements, the portion of the glue wheel shaft which carries a driving wheel or sprocket being in section.

Fig. 2 represents a section on line 2—2 of Fig. 1.

Fig. 3 represents a section of the device

on a line such as indicated at 3—3 in Fig. 2 looking in the direction of the arrow.

Fig. 4 represents a detail section on line 4—4 of Fig. 3, looking in the direction of the arrow.

Similar reference numerals indicate similar parts in all of the views.

The glue box or receptacle 12 is of any suitable proportion and capacity, and is preferably provided with a tight-fitting cover 13 having a suitable handle or knob 14. At the ends of the box are ears 15 having openings by means of which the box can be supported in proper position on cross-70 rods or shafts of the folding machine in which the gluing device is employed. Said ears are removably secured in place as by suitable screws 16.

The box has a longitudinal partition 17 75 (Fig. 2) to divide the box into a glue chamber 18 and a water chamber 19, suitable connections being made, as by means of a pipe 20, to either admit steam into the water chamber or to keep up a constant supply of 80 water in said chamber at a temperature sufficient to provide vapor in the closed receptacle to keep the glue in chamber 18 in a proper condition of fluid consistency, and to keep the wheel 27 moist. 85

The bottom of the chamber 18 is slotted as at 21 in order to permit the glue wheel presently described to project below the bottom of the box.

Extending from one wall of the box, 90 through the partition 17, and nearly to the opposite wall of the box is a cylindrical bearing 22. Rotatively mounted in said bearing 22 is an eccentric bushing 23. A shaft 24 is mounted in said bushing, the 95 outer end having a suitable drive wheel 25 connected thereto, and the inner end having secured to it the hub 26 of the glue wheel 27.

Obviously, if no provision were made to prevent it, glue would escape from chamber 18 through the slot 21. To prevent such escape, and to make provision so that only a portion of the glue wheel will be immersed in glue, I provide an inclined slotted wall 28 (compare Figs. 3 and 4) reaching from the bottom of the box up to the hub 26. Obviously it might extend farther up. Said wall 28 is slotted to admit the wheel 27. A plate 29, preferably of brass, is secured to the wall 28, as by means of screws 30. 110 This plate 29 is so accurately slotted that the sides of the same will so closely fit the

sides of the wheel 27 as to prevent the passage of glue between the sides of the wheel and the sides of the slot. When the machine is in operation there is a slight space 5 between the bottom of the slot in the brass plate 29 and the periphery of the glue wheel so as to permit a thin film of glue to be carried downwardly by the glue wheel when the latter is revolved in the direction of the 10 arrow in Fig. 3.

The outer end of the eccentric bushing 23, outside of the glue box has clamped thereon the hub 31 of an arm 32, the latter having a link 33 pivoted to it at 34, the other end 15 of the link having a suitable handle 35. The lower edge of the link 33 is provided with a series of notches 36, either one of which may be engaged with a pin 37 projecting from the outer wall of the box said pin having a 20 flattened portion as indicated by dotted lines in Fig. 1 to fit one of the notches 36. A spring 38 having one end connected to the link and the other end being connected to the wall of the box, keeps the link 33 with 25 one of its notches engaged by the pin 37.

The means last described enables me to vary the thickness of the film of glue taken out by the glue wheel, or to completely close the space between the periphery of the 30 wheel and the bottom of the slot in plate 29. This is because, by means of the link 33 having the handle 35, I can swing the arm 32 so as to rotate the eccentric bushing 33 sufficiently to finely adjust the vertical 35 position of shaft 24 which carries the glue wheel 27. As has been stated, the sides of the slot in plate 29 fit so closely to the sides of the glue wheel that no appreciable amount of glue can escape there-between. 40 By rotatively adjusting the eccentric bushing 23, I can either entirely close or vary the space between the periphery of the wheel and the bottom of the slot in plate 29.

To provide a support for the blanks, especially when the latter are made of thin paper, so that the blanks will contact with the portion of the glue wheel which projects below the bottom of the box, I secure a bracket 40 to one side of the box by means 50 of a screw 39, the lower end of said bracket carrying a stud 41 which is provided with a slit for a thin blade or support 42. One end of the stud 41 is screw threaded and is provided with a nut 43 by means of which 55 the stud can be manipulated to permit the blade or plate 42 to be swung nearer or farther from the periphery of the glue wheel, and then clamp it in its adjusted position.

60 Owing to the fact that the top of the box is entirely closed, it is practically impossible for dust or lint to get into the box to mix with the glue, or for any great amount of vapor rising from chamber 19 to escape. 65 Only the lower portion of the wheel is ex-

posed to apply glue to the blanks, another portion of the wheel projecting through the slot of the end wall 28, 29. The edge which is presented by the bottom of the slot in plate 29 constitutes a doctor which determines the thickness of the film of glue carried past it by the periphery of the wheel, or serves to prevent the passage of any glue when the wheel is not rotating, all according to the degree of adjustment of the wheel 70 toward and from said doctor. 75

As the only opening in the box is the bottom one 21, and as said opening is nearly closed or filled by the lower portion of the wheel 27, the vapor from the warmed water 80 in chamber 19 keeps the glue wheel moist. The vapor has access to all portions of the wheel that are not immersed in the glue, and the portion so immersed comprises only a small sector of the wheel that is bounded 85 by the inclined slotted wall 28 and the level of the surface of the glue in chamber 18. When the machine is stopped, the glue keeps the immersed portion of the wheel from drying, while the vapor which has access to 90 all other portions of the wheel prevents the drying of the film of glue which has adhered to said other portions. Consequently the glue wheel never accumulates a coating 95 of dry glue, during stoppage, which would interfere with proper operation when the machine is started again to run.

The inclined slotted wall 28 is tangential to a circle surrounding the axis of the glue wheel whereby said wall not only serves to 100 limit the immersed area of the wheel to a smaller sector than if the lower half of the wheel were immersed, but also causes the rotation of the wheel in the direction of the arrow, Fig. 3, to effect a constant stirring 105 up or circulation of the glue, due to the current produced by the revolving wheel, such current being deflected backwardly by the inclined wall.

Having now described my invention, I 110 claim:

1. In mechanism of the character described, a glue receptacle having a slot, a wheel mounted in the receptacle and having a portion projecting through said slot, all 115 other portions of the receptacle being closed, and means for subjecting the wheel to the action of vapor to prevent drying when the wheel is stationary.

2. In mechanism of the character described, a glue receptacle having a slotted end wall, a wheel having its lower portion exposed and having another portion projecting through the slot of said end wall into the glue receptacle, said end wall being tangential to a circle surrounding the axis of the wheel, and means for adjusting the wheel edgewise in said slot. 120 125

3. In mechanism of the character described, a glue receptacle, a wheel having its 130

- lower portion exposed, a slotted member through which another portion of the wheel projects, said slotted member being tangential to a circle surrounding the axis of the 5 wheel, the slot of said member having its sides closely fitting the sides of the wheel, the end of said slot forming a doctor for the periphery of the wheel, and means for adjusting the wheel edgewise in said slot.
- 10 4. In mechanism of the character described, a glue receptacle having a slotted end wall, a cylindrical bearing adjacent the upper portion of said end wall, an eccentric bushing mounted in said bearing, a shaft 15 mounted in said bushing and having a glue wheel a portion of which projects through the slot in said end wall, a lower portion of said wheel being exposed to apply glue to blanks, and means for rotatively adjusting 20 said eccentric bushing.
5. In mechanism of the character described, a glue receptacle having a slotted end wall, a cylindrical bearing adjacent the upper portion of said end wall, an eccentric bushing mounted in said bearing, a shaft 25 mounted in said bushing and having a glue wheel a portion of which projects through the slot in said end wall, a lower portion of said wheel being exposed to apply glue to blanks, and means for rotatively adjusting 30 said eccentric bushing, said means comprising an arm carried by the eccentric bushing,
- a link pivoted to said arm, and means for locking said link in either one of a plurality of positions. 35
6. The combination with a glue box having a slot in its bottom, of a glue wheel the lower portion of which projects through said slot, a bracket secured to the side of the box and extending below the plane of 40 said bottom, and a blank-supporting blade adjustably connected with said bracket and extending under the wheel.
7. The combination with a glue box having a glue wheel the lower portion of which 45 is exposed to apply glue to blanks, of a blank support opposite said lower portion of the wheel, said support comprising a flexible strip adjustably connected with said box. 50
8. In mechanism of the character described, a closed receptacle having a glue chamber and a water chamber, said glue chamber having a slotted wall, a wheel having a portion of its periphery extending through said slot, an under portion of the wheel being exposed to apply glue to passing blanks, and means for permitting vapor from the water chamber to have constant access to all portions of the wheel not immersed in glue. 55

In testimony whereof I have affixed my signature. ELIE W. LABOMBARDE.
